UNITED STATES PATENT OFFICE.

JOHN ROGERS, OF NEW YORK, N. Y.

DESIGN FOR A GROUP OF STATUARY.

Specification forming part of Design No. 5,854, dated May 14, 1872.

I, JOHN ROGERS, of New York, in the county and State of New York, have invented and produced a new and original Design for a Group of Statuary, of which the following is a specification:

The nature of my design is fully represented in the accompanying photographic illustration.

The group consists of two boys and a horse, and is called "We Boys." The horse is standing in a brook. The boy in front, on his back, has lost the reins, and is trying to regain them

with the stick in his hand, and at the same time is frightened by the threatening actions of the horse, which is irritated by the second boy, who is trying to climb on his back from the bank.

I claim as my invention—

The design for a group of statuary, as shown.

JOHN ROGERS.

Witnesses:

M. COLWELL,
CHAS. CALVERLEY.
